UNITED STATES PATENT OFFICE.

GUSTAVUS A. GOLDSMITH, OF NEW YORK, N. Y.

PEN-HOLDER.

SPECIFICATION forming part of Letters Patent No. 351,832, dated November 2, 1886.

Application filed July 23, 1886. Serial No. 208,837. (No model.)

To all whom it may concern:

Be it known that I, GUSTAVUS A. GOLDSMITH, a citizen of the United States, and a resident of New York, in the county of New York and State of New York, have invented certain new and useful Improvements in Pens; of which the following is a specification.

My invention relates to an improvement in pen-holders, and has special reference to the construction of the tip and elastic nib thereof and the method of attaching the elastic nib in the tip.

Heretofore the elastic nib has mostly been held to the tip by—

15 First. The simple elastic expanding of the nib. This method is insecure and also practically requires that the tip should be either seamless or of stiff and expensive metal.

Second. By placing the nib within the tip; 20 then punching a hole through both, and then passing a rivet through the hole and riveting it. This method requires two operations—one to punch the hole and the other to introduce and secure the rivet. Moreover, such riveted tips are usually quite insecure so far as the holding of the nib is concerned, because of the mechanical difficulties which attend properly upsetting the inner ends of the rivets, considering the rapidity with which this must be 25 done to secure necessary cheapness.

Third. A hole has been made in the nib and then the metal of the external tip has been punched into this hole. This method is quite satisfactory in its results, but requires three 35 operations: First, punching the hole in the nib; second, properly registering this hole with the punch; and, third, operating the punch.

By my invention I secure the said parts to each other in a most effective manner by one, 40 and that a very simple operation.

Figure 1 illustrates a side plan elevation of the invention. Fig. 2 illustrates a longitudi-

nal section on a horizontal plane through Fig. 1.

A is the tip, preferably made of metal, and 45 it may be seamless or seamed.

B is the nib with separated edges b, as usual.

C is the handle. The nib is inserted into the tip, preferably, but not necessarily, with a snug fit. A suitably-constructed mandrel is 50 then inserted within the nib. A punch then cuts the two little semicircular metallic pieces D from both the tip and the nib and bends them down inwardly, one extending forwardly and the other rearwardly. A part of the metal, D', 55 is left unaltered between these two bent-down pieces. Thus the nib is securely locked either against inward or outward movement by the simple and single operation of the punch.

Having described my invention, I claim— 60

1. The described method of constructing pen-holder tips, consisting in inserting the nib within the tip, and then by a single mechanical operation cutting out and interlocking portions of the tip and the nib, whereby the 65 nib will be locked relative to the tip both inwardly and outwardly.

2. As a new article of manufacture, the herein-described pen-holder, consisting of handle C, tip A, nib B, the nib B and tip A being 70 united to each other by inwardly-depressed portions D D, cut from both the tip and the nib, and running lengthwise thereof, and pointing in opposite directions, and a portion of the tip left between the said depressed portions and in substantially its original position, as set forth.

Signed at New York, in the county of New York and State of New York, this 20th day of July, A. D. 1886.

GUSTAVUS A. GOLDSMITH.
